(57) **CLAIM**

The ornamental design for a display screen with icon, as shown and described.

DESCRIPTION

FIG. 1 is a front view of a display screen with icon showing my new design; and,

FIG. 2 is an enlarged view of the icon shown in FIG. 1. The broken line showing of the remainder of the display screen forms no part of the claimed design.

1 Claim, 2 Drawing Sheets

FIG. 1

FIG. 2
